(57) **CLAIM**

The ornamental design for a bar lock assembly guide plate, as shown and described.

DESCRIPTION

FIG. 1 is a top plan view of one embodiment of a bar lock assembly guide plate showing my new design;

FIG. 2 is a left end view thereof;

FIG. 3 is a right end view thereof;

FIG. 4 is a right side elevational view thereof; with the left side elevational view being a mirror image thereof;

FIG. 5 is a bottom plan view thereof;

FIG. 6 is a top plan view of a second embodiment of my new design;

FIG. 7 is a left end view thereof;

FIG. 8 is a right end view thereof;

FIG. 9 is a right side elevational view thereof; with the left side elevational view being a mirror image thereof;

FIG. 10 is bottom plan view thereof;

FIG. 11 is a top plan view of a third embodiment of my new design;

FIG. 12 is a left end view thereof;

FIG. 13 is a right end view thereof;

FIG. 14 is a right side elevational view thereof; with the left side elevational view being a mirror image thereof; and,

FIG. 15 is bottom plan view thereof.
